COMBINATION DOOR AND PANEL

Paul H. Lauer, Akron, Ohio

Application December 31, 1957, Serial No. 706,475

5 Claims. (Cl. 20—35)

The invention relates in general to a combination door with panels and more particularly to a combination door with panels having the frames thereof made of resilient and bendable high impact rigid thermosetting plastic.

An object of the invention is to provide a combination door and panel construction wherein the frame is constructed of resilient and bendable high impact rigid thermosetting plastic.

Another object of the invention is to provide a combination door and panel construction wherein the frame includes hollow rectangular thermosetting plastic side, top, bottom, and cross-piece members.

Another object of the invention is to provide the side, top and bottom members with beveled end portions and the end portions secured together by anchor members to form four ninety degree corners.

Another object of the invention is to provide the side, top, bottom, and cross-piece members with a new and novel lip shoulder construction for holding the glass and screen panels within the door frame.

Another object of the invention is to provide a door which is exceptionally durable, strong, and which is unaffected by cold and heat and which will not burn and which will not chip, crack, pit, rust, rot or oxidize.

Another object of the invention is to provide a door frame with fixedly bendable reinforcing means to align the door against a door molding.

Another object of the invention is to provide a door frame with fixedly bendable reinforcing means mounted with returnably bendable hollow means, the fixedly bendable reinforcing means overpowering the returnably bendable means to align the door against a door molding.

Other objects and a better understanding of the invention may be had by referring to the following description and claims, taken in conjunction with the accompanying drawing, in which:

Figure 1 is a view of the door and panel of the present invention shown mounted within the framework of a conventional door molding;

Figure 2 is an edge view of the swingable side of the door showing the door out of alignment with the door molding;

Figure 3 is a view taken along the section line 3—3 of Figure 1;

Figure 4 is a view taken along the section line 4—4 of Figure 1;

Figure 5 is a view taken along the section line 5—5 of Figure 1;

Figure 6 is a view taken along the section line 6—6 of Figure 1;

Figure 7 is a view taken along the section line 7—7 of Figure 1;

Figure 8 is a view taken along the section line 8—8 of Figure 1;

Figure 9 is a view taken along the section line 9—9 of Figure 1;

Figure 10 is a plan view showing the beveled ends of

the frame members and the ninety degree anchor members before assembly;

Figure 11 is the same as Figure 7 but does not show a reinforcing means mounted within the hollow construction;

Figure 12 is the same as Figure 9 but does not show a reinforcing means mounted within the hollow construction;

Figure 13 is a view taken along the section line 13—13 of Figure 1; and

Figure 14 is a view taken along the section line 14—14 of Figure 1.

The door 10 of the present invention includes a frame 14 within which are two panels 11 and 12, and a third panel 13 referred to as a kick panel. The panels 11 and 12 may be either constructed of glass or screen. In winter weather, the glass panels may be easily mounted in the door frame 14. In summer weather, the glass panels would be changed for screen panels which may also be easily mounted in the door frame 14. The kick panel 13 is made of durable structure glass and will not crack, chip, or mar under any physical or chemical conditions. The frame 14 is constructed of a first or hingeable side member 15, a second or swingable side member 25, a top member 17, a bottom member 18, a first cross-piece member 19 intermediate the top member 17 and the bottom member 18, and a second cross-piece member 20 intermediate the bottom member 18 and the first cross-piece member 19. The first side member 15 has hinges 21 and 22 attached thereto to fasten the door to a molding 25. The second side member 16 has a handle 23 attached thereto to facilitate the opening and closing of the door 10. Figures 1 and 2 best show the relative location of the component parts of the door 10 with respect to each other and Figures 3 through 12, inclusive, illustrate each component part in more detail.

With specific reference to Figures 3 through 12, inclusive, of the drawings, the members 15, 16, 17, 18, 19 and 20 have front side walls 31, back side walls 32, an outer edge wall 33 and an inner edge wall 34. The front side wall 31 and the back side wall 32 each have first ends 45 and 46 and second ends 47 and 48, see particularly Figure 4. The outer edge wall 33 integrally connects the first end 45 of the front side wall 31 to the first end 46 of the back side wall 32. The inner edge wall 34 integrally connects the second end 47 of the front side wall 31 to the second end 48 of the back side wall 32. The side walls 31 and 32 and the edge walls 33 and 34 form a substantially hollow rectangular construction designed by the number 30. The construction 30 is extruded from high temperature extruding machines and is made of high impact rigid thermosetting plastic. The plastic is resilient and upon being bent will return to its normal or original position. The side walls 31 and 32 and the edge walls 33 and 34 have an outer surface 35 and an inner surface 36. The outer surface 35 and the inner surface 36 define a wall section therebetween of substantially uniform thickness throughout.

The inner edge wall 34 defines a lip shoulder 40. The lip shoulder 40 receives a panel frame 37 for either a screen or a glass. The panel frame 37 fits against the lip shoulder 40 and is held therein by a clip 38 and a screw 39. The lip shoulder 40 comprises a first wall portion 41, a second wall portion 42, and a third wall portion 43. The first wall portion 41 of the lip shoulder 40 extends substantially perpendicular from the second end 48 of the back side wall 32. The first wall portion 41 has a terminating end 50 intermediate the distance of the back side wall 32 and the front side wall 31. The second wall portion 42 of the lip shoulder 40 extends substantially perpendicular from the terminating end 50 of the first wall portion 41 of the lip shoulder 40. The

second wall portion 42 has a terminating junction 51. The third wall portion 43 of the lip shoulder 40 extends in an arcuate path from the second end 47 of the front side wall 31 and integrally connects to the terminating junction 51 of the second wall portion 42 of the lip shoulder 40. The inner surface 36 of the second wall portion 42 and the inner surface 36 of the third wall portion 43 of the lip shoulder 40 join each other at the terminating junction 51 and divergently extend therefrom. The inner surfaces 36 of the second wall portion 42 and the third wall portion 43 of the lip shoulder 40 are spaced apart with respect to each other at the second end 47 of the front side wall 31 and at the terminating end 50 of the first wall portion 41 of the lip shoulder 40.

The first end 45 of the front side wall 31 and the first end 46 of the back side wall 32 have first and second projection portions 52 and 53, respectively, extending from the outer edge wall 33. The first and second projection portions 52 and 53 have terminating end edges 54 and 55, respectively, with the terminating end edges 54 and 55 having inturn flanges 56 and 57, respectively spaced apart and facing each other.

With specific reference to Figure 5 of the drawings, the first cross-piece member, designated by 19, is substantially the same construction as the first and second side members 15 and 16, except that the outer edge wall 33 of the hollow construction 30 has a projection 49 which in combination with the lip shoulder 40 defines a channel to receive a panel frame 37. The second cross-piece member 20 is not shown in detail, but likewise has substantially the same construction as Figure 5.

Figure 3 of the drawing shows the method that the ends 70 of the first cross-piece member 19 and the second cross-piece member 20 are fastened to the first side member 15 and the second side member 16. The inner and outer edge walls 33 and 34 of the first and second side members 15 and 16 have apertures 59. The outer and inner edge walls 33 and 34 of the first and second cross-piece members 19 and 20 also have apertures 60. A screw 61, having a head 62 to abut against the outer edge wall 33 of the first and second side members 15 and 16 and also having a threaded end 63, passes through the aperture 59 of the outer and inner edge walls 33 and 34 of the first and second side members 15 and 16. A cylindrical metal cross-piece 64 having a threaded aperture 65 fits in the aperture 60 of the outer and inner edge wall 33 and 34 of the first and second cross-piece members 19 and 20. The aperture 65 is in alignment with the screw 61. The threaded end 63 of the screw 61 engages the threaded aperture 65 of the cylindrical cross-piece 64 to fasten the ends 70 of the first and second cross-piece members 19 and 20 securely against the first and second side members 15 and 16.

The first side member 15 has end portions 72, the second side member 16 has end portions 73, the top member 17 has end portions 74, and the bottom member 18 has end portions 75. Figure 10 of the drawings shows the bottom member 18 and the second side member 16 before assembly. Although Figure 10 illustrates a specific corner of the door 10, the other three corners of the door 10 are substantially the same in construction. The end portions 73 and 75 of the members 16 and 18 are beveled at substantially forty-five degrees. The end portions 73 and 75 interfit with each other and form a substantially ninety degree corner. The outer edge wall 33 of the end portions 73 and 75 of the members 16 and 18 have apertures 76. Residing within the hollow construction 30 of the end portions 73 and 75 is a right-angle anchor member 77, preferably constructed of metal. The anchor member 77 securely fastens the end portions 73 and 75 together to form corners. The anchor member 77 has apertures 78 in alignment with aperture 76 of the end portions 73 and 75. Threaded members 79 engage the apertures 76 of the end portions 73 and 75 and the apertures 78 of the anchor member 77 to securely fasten

the anchor member 77 within the right angle corners. Adhesive means 85 is applied to the anchor members 77. The adhesive means 85 contacts the inner surface 36 of the corners of the door 10 and hardens to form a moisture-tight seal. The hardened adhesive means 85 prevents moisture seepage through the door frame 14.

Residing against the inner surface 36 of the hollow construction 30 of the first and second side members 15 and 16 and the top member 17 is a first reinforcing means 80, a second reinforcing means 81, and a third reinforcing means 82, respectively. The reinforcing means 80, 81 and 82 are fastened to the inner surface 36 of the hollow construction 30 by adhesive means 85. The adhesive means 85 is applied to the reinforcing means 80, 81 and 82 before the reinforcing means is inserted into the hollow construction 30. The adhesive means 85 contacts the inner surface 36 of the hollow construction 30 and hardens to form a moisture-tight seal. The reinforcing means 80, 81 and 82 is preferably constructed of aluminum, but it is understood that any type of fixedly bendable material may be used. The door herein described constitutes three separate reinforcing means, but the door 10 may be constructed with the reinforcing means omitted from the top member 17, see Figure 11, leaving reinforcing means in only the two side members 15 and 16, or with the reinforcing means omitted from the second side member and top member 16 and 17 leaving reinforcing means in only the first side member 15. Figure 12 shows the second side member 16 with no reinforcing means.

The first reinforcing means 80 is used for fastening the hinges 21 and 22 to the first side member 15. The hinges 21 and 22 are fastened to the member 15 by threaded means 105 that engage the reinforcing means 80.

The third reinforcing means 82 is used for fastening the handle 23 to the second side member 16 by threaded means 106.

For the purpose of clarity, the term "fixedly bendable" is used herein to express the idea that once an object is bent by an outside force, that object retains the bent position. The term "returnably bendable" is used herein to express the idea that once an object is bent by an outside force, that object returns to the original position or to the position it had before being bent. Figure 2 of the drawings illustrates an edge of the second or swingable side member 16 of the door 10. Line 27 is an imaginary line and represents a warped or inclined door molding 25. The door 10, as manufactured is not warped but is true with the frame members lying in a true plane. When the true door is mounted in a warped or crooked molding, the true door will depart from the molding, as illustrated by the imaginary line 27. The door frame 14 because of its bendable properties may be made, by applying an outside force, to fit snugly against the warped or crooked door molding 25. The bending of the door bends both the reinforcing means as well as the plastic frame members. The bendable reinforcing means after once bent remain fixedly bent, and they have sufficient strength to overpower the bending properties of the plastic frame members and thus hold the plastic members of the door against the door molding. In other words, a true door may be bent to fit an untrue molding with the present invention.

The first, second, and third reinforcing means 80, 81 and 82 are fixedly bendable and thereby they fixedly hold the first and second side members 15 and 16 and the top member 17 from bendably returning to their original position. This property of being fixedly bendable allows the door frame to align against an offset or crooked door molding.

Preferably the bottom member 18 does not contain reinforcing means, although it may be reinforced. Without a reinforcing means, the bottom member 18 is therefore returnably bendable to provide a wide range of flexibility to the door frame 14. The door of the present invention can withstand a great deal of "whipping".

The bottom edge of the bottom member has an adjustable cross-member 26 which may be adjusted to fit the bottom of the floor beneath the door. The bottom edge of the cross-member 26 may be fitted with a rubber lip 34 to seal the door 10 at the floor level.

The door 10, herein described, has a greater amount of flexibility than an ordinary wood or aluminum door. An aluminum door, for example, hinged to a molding and with the top member of the aluminum door held by an outside force to the molding, the bottom corner opposite the hinged side of the door could then be pulled out by an outside force only two to three inches from the door molding 25. This is due to the aluminum door having very little flexibility. If the door 10 of the present invention were placed in the same position and the same outside forces were applied as in the aluminum door, the bottom corner opposite the hinged member 15 could be pulled out as much as nine to twelve inches, or more, from the door molding 25. This extreme flexibility of the door 10 is essential in doors that are roughly used and banged against the door molding 25 to a great extent. Without this flexibility, the door would eventually crack along the corners nearest to the hinged member 15.

Although I have described my invention with a certain degree of particularity, it is understood the present disclosure has been made only by way of example and that numerous changes in the details of construction and the combination and arrangements of parts may be resorted to without departing from the spirit and the scope of the invention as hereinafter claimed.

What is claimed is:

1. In a door frame having panel means, said door frame having members, one of said members having hingeable means, another of said members being swingable against a door molding, said members having side walls interconnected by inner and outer edge walls, said walls having inner and outer surfaces, said walls forming a substantially hollow rectangular construction, said construction being resilient and comprising high impact rigid thermosetting plastic, said hollow construction being returnably bendable to an original position, said members having end portions beveled at substantially forty-five degrees, said end portions interfitting with one another to form four substantially ninety degree corners, said inner edge wall having lip shoulder means, reinforcing means residing against said inner surface of said hollow construction of said members, said reinforcing means allowing said members to be fixedly bendable and thereby fixedly holding said members from bendably returning to their original position to align said frame against said door molding, said panel means having edges interfitting against said lip shoulder means.

2. In a door frame having panel means, said door frame having first and second side members and top and bottom members, said first side member having hingeable means, said second side member being swingable against a door molding, said first and second side and top and bottom members having side walls interconnected by inner and outer edge walls, said walls having inner and outer surfaces, said walls forming a substantially hollow rectangular construction, said construction being resilient and comprising high impact rigid thermosetting plastic, said hollow construction being returnably bendable to an original position, said members having end portions beveled at substantially forty-five degrees, said end portions interfitting with one another to form four substantially ninety degree corners, said inner edge wall having lip shoulder means, reinforcing means residing against said inner surface of said hollow construction of said first and second side and top members only, said reinforcing means allowing said first and second side and top members to be fixedly bendable and thereby fixedly holding said first and second side members and said top member from bendably returning to their original position to align said frame against said door molding, said bottom

member being returnably bendable to provide a wide range of flexibility to said door frame, said panel means having edges interfitting against said lip shoulder means.

3. In a door frame having panel means, said door frame having first and second side members and top and bottom members, said first side member having hingeable means, said second side member being swingable against a door molding, said first and second side and top and bottom members having side walls interconnected by inner and outer edge walls, said walls having inner and outer surfaces, said walls forming a substantially hollow rectangular construction, said construction being resilient and comprising high impact rigid thermosetting plastic, said hollow construction being returnably bendable to an original position, said members having end portions beveled at substantially forty-five degrees, said end portions interfitting with one another to form four substantially ninety degree corners, said inner edge wall having lip shoulder means, reinforcing means residing against said inner surface of said hollow construction of said first side member, threaded elements extending through said hollow construction and engaging said first reinforcing means to securely fasten said hingeable means to said first member, said reinforcing means being fixedly bendable and thereby fixedly holding said first side member from bendably returning to its original position to align said frame against said door molding, said panel means having edges interfitting against said lip shoulder means.
4. In a door frame having panel means, said door frame having first and second side members and top and bottom members, said first side member having hingeable means, said second side members having handle means and being swingable against a door molding, said first and second side and top and bottom members having side walls interconnected by inner and outer edge walls, said walls having inner and outer surfaces, said walls forming a substantially hollow rectangular construction, said construction being resilient and comprising high impact rigid thermosetting plastic, said hollow construction being returnably bendable to an original position, said members having end portions beveled at substantially forty-five degrees, said end portions interfitting with one another to form four substantially ninety degree corners, said inner edge wall having lip shoulder means, reinforcing means residing against said inner surface of said hollow construction of said first and second side members only, threaded elements extending through said hollow construction of said second side members and engaging said reinforcing means therein to securely fasten said handle means to said second member, said reinforcing means of said first and second members being fixedly bendable and thereby fixedly holding said first and second side members from bendably returning to their original position to align said frame against a door molding to provide a wide range of flexibility to said door frame, said panel means having edges interfitting against said lip shoulder means.
5. In a door frame having panel means, said door frame having first and second side members and top and bottom members, said first side member having hingeable means, said second side member having handle means and being swingable against a door molding, said first and second side and top and bottom members having side walls interconnected by inner and outer edge walls, said walls having inner and outer surfaces, said walls forming a substantially hollow rectangular construction, said construction being resilient and comprising high impact rigid thermosetting plastic, said hollow construction being returnably bendable to an original position, said members having end portions beveled at substantially forty-five degrees, said end portions interfitting with one another to form four substantially ninety degree corners, said inner edge wall having lip shoulder means, first reinforcing means residing against said inner surface of

said hollow construction of said first side member, threaded elements extending through said hollow construction and engaging said first reinforcing means to securely fasten said hingeable means to said first member, second reinforcing means residing against said inner surface of said hollow construction of said top member, adhesive means for connecting said reinforcing means to said top member, third reinforcing means residing against said inner surface of said hollow construction of said second side member, threaded elements extending through 10 said hollow construction and engaging said third reinforcing means to securely fasten said handle means to said second side member, said first, second and third reinforcing means being fixedly bendable and thereby fixedly holding said first and second side members and 15

5 said top member from bendably returning to their original position to align said frame against said door molding, said bottom member being unreinforced and returnably bendable to provide a wide range of flexibility to said door frame, said panel means having edges interfitting against said lip shoulder.
